X 00000

July 31, 1790

The United States.

To all whom these Presents shall come, greeting.

Whereas Samuel Hopkins of the City of Philadelphia and State of Pennsylvania hath discovered an Improvement, not known or used before, such Discovery, in the making of Potash and Pearlash, by some Apparatus and Process, that is to say, in the making of Pearlash 1st by burning the raw Ashes in a Furnace, 2^d by digesting and boiling them when so burnt in Water, 3rd by drawing off and setting the sly, and 4th by boiling the dry into salts which then are the true Pearlash; and also in the making of Potash by placing the Pearlash so made as aforesaid, which Operation of burning the raw Ashes in a Furnace, preparatory to their Digestion and Boiling in Water, is new, knows little Potassium; and produces a much greater quantity of Salt: These are therefore in pursuance of the Act, entitled "An Act to promote the Progress of useful Arts," to grant to the said Samuel Hopkins, his Heirs, Administrators and Assigns, for the term of fourteen Years, the sole and exclusive Right and Liberty of using and vending to others the said Discovery, of burning the raw Ashes previous to their being digested and boiled in Water, according to the true Intent and Meaning, of the Act aforesaid. In Testimony whereof I have caused these letters to be made patent, and the seal of the United States to be affixed. Given under my Hand at the City of New York this thirty first Day of July in the Year of our Lord one thousand seven hundred Ninety.

City of New York July 31st 1790. -

I do hereby certify that the foregoing Letters patent were delivered to me in pursuance of the Act intituled "An Act to promote the Progress of useful Arts;" these I have examined the same, and find them conformable to the said Act.

S^r.
Samuel Hopkins

Adam: Randolph Attorney General for the United States. -
